BACKLESS GARMENT

Carolyn G. Schnurer, New York, N. Y.

Application May 25, 1948, Serial No. 28,978

2 Claims. (Cl. 2—67)

1

The present invention relates to a lady's backless garment, and, more particularly, to a backless garment for outer wear, of the type used in sports activities or for sunning oneself, such as bathing suits, sun dresses and the like.

The wearing of backless garments of the character described presents a problem to women, particularly to those who are accustomed to or require the use of a brassière, for the reason that the wearing of a brassière with such garments make the wearer's back unsightly because of the untidy appearance of the exposed brassière portions and for the further reason that it covers a part of the back to defeat, at least in part, the purpose of the garment. On the other hand, the omission of a brassière leaves the front of the wearer's body unsightly because of the lack of a proper contour and uncomfortable because of the lack of adequate bust support.

While in the case of certain backless garments of the character described, such as bathing suits, an endeavor has been made to solve the foregoing difficulties with built in brassière portions, such attempt at solution has been found inadequate even for such garments and totally inadequate for dresses or the like, for the reasons that will be obvious to makers and wearers of the garment alike.

It is the object of the present invention to provide backless garments of the character described, for women, which will provide ample and adequate support and contour for the bust, without the use of any brassière, either separate or built in.

It is another object of the present invention to provide a backless garment of the character described in which the bust supporting means are adjustable to the requirements of the individual wearer.

It is also an object of the present invention to provide a backless garment of the character described in which the tendency of the garment to gap away from the body at the sides will be reduced and which is otherwise neat and attractive in appearance.

It is a further object of the present invention to provide a backless garment of the character described which is relatively simple and economical to produce and which is easy and convenient to use.

The foregoing and other advantages and superiorities of the backless garments of the present invention will become more readily apparent to those skilled in the art from the embodiment thereof, in the form of a bathing suit, shown in

the accompanying drawings. It is to be understood, however, that such embodiment is shown by way of illustration only, to make the principles and practice of the invention more readily comprehensible, and without any intent of limiting the invention to the specific details therein shown.

In the drawings:

Fig. 1 is a view in front elevation of a bathing suit embodying the present invention, shown as worn on the body;

Fig. 2 is a side elevational view of the same; and

Fig. 3 is a fragmentary, enlarged, plan view of the top portion of the garment shown in Figs. 1 and 2, showing structural details thereof.

Referring more specifically to the accompanying drawings, the bathing suit 10, shown as an illustrative embodiment of the present invention, comprises a lower portion 11 encompassing the lower portion of the body, on all sides, up to about 15 the waistline thereof, and an upper portion 12 extending from the waistline upward, which is backless, tapering toward the front to cover only the front of the wearer's body.

The top portion 12 may be formed with breast 25 receiving cups or pockets 13 which may be shaped, as by the suitably placed darts 14, in a manner readily understood by those skilled in the art. It will also be readily understood that the cups 13, although accommodating the breasts, will not support them to any degree nor provide the desired contour therefor.

The top section 12 is provided with an approximately V-shaped neckline 15 terminating at the top in shoulder points 16, to one of which may be secured or formed integrally therewith the neck band 18 having the eyes 19 defined by the eyelets 20 at its free end. The other point 21 may have secured thereon a hook 21 for engagement with a selected eye 19 to provide adjustable means for securing the top of the garment on the body, to suit the individual wearer.

The neckline 15 may also be formed with a downwardly directed notch or recess 23 at its base. Bands or belts 24 extend from the opposite 45 edges of the recess 23, preferably continuously with the edges of the neckline 15. The bands 24, which are oppositely directed, in a diagonally downward direction, cross one another over the recess 23 and are of sufficient length to be passed 50 each under the pocket, or cup, 13, on the opposite side of the garment, to outline and support the breast nested therein, and to be passed around the side of the wearer, to reduce the tendency of the garment to gap at that point, and to cross one 55 another at the back of the garment and to be

brought forward to the front thereof for interengagement with one another, to keep them in proper position. The interengagement between the bands 24 at the front of the garment may, preferably, be adjustable, and may also comprise the eyes 25 with eyelets 26 at the end of one band, and a cooperating hook 27 fixedly or adjustably secured to the end of the other band 24.

This completes the description of one embodiment of the present invention. It will be readily apparent that the invention provides, by simple and economical means, a backless garment which is readily adjustable to the individual wearer; which provides the desired contour and ample and adequate support for the wearer's bust; in which the bust supporting means is adjustable to the needs of the individual wearer; in which gaping at the sides of the garment is reduced to a minimum; and which is otherwise neat and attractive in appearance and easy and convenient to wear.

It will also be apparent that numerous variations and modifications in the garments of the present invention may readily be made by any skilled in the art, in accordance with the principles of the invention hereinabove set forth and without the use of any inventive ingenuity. I desire, therefore, to be protected for any and all such variations and modifications that may be made within the spirit of the present invention and the scope of the claims hereto appended.

What I claim is:

1. In a lady's garment, an upper front portion having a pair of breast covering sections, each of said sections having upwardly converging edges forming shoulder points, the contiguous edges of said sections forming a downwardly converging neckline, the further edges of said sections extending diagonally downwardly along the sides and meeting approximately at the waist line to form a substantially backless garment, a neck band secured at one end to one of said shoulder points, means at the free end of said neck band and other of said shoulder points for detachably securing one to the other, said breast receiving sections having a vertically extending separation formed between them along their upper portions opening into the neckline at approximately the center of the garment front, a relatively narrow band continuous with the marginal portion of the neckline edge of each of said sections, said bands extending in opposed directions across the front

of the garment, crossing at the said separation in a diagonally downward direction, said bands each being of a length to extend diagonally around the sides and back of the garment and to the front thereof for the interengagement of its free end with the free end of the companion band.

2. In a lady's garment, an upper front portion having a pair of breast covering sections, said sections having parts shaped to fit about the breast, each of said sections having upwardly converging edges forming shoulder points, the contiguous edges of said sections forming a downwardly converging neckline, the further edges of said sections extending diagonally downwardly along the sides and meeting approximately at the waist line at the back to form a substantially backless garment, a neck band secured at one end to one of said shoulder points, means at the free end of said neck band and the other of said shoulder points detachably secured one to the other, said breast receiving section having a vertically extending separation formed between them along their upper portions opening into the neckline at approximately the center of the garment front, a relatively narrow band continuous with the marginal portion of the neckline edge of each of said sections, said bands extending in opposed directions across the front of the garment, crossing at the separation, in a diagonally downward direction adjacent the bottom of the shaped portions of said breast covering sections, said bands each being of a length to extend diagonally around the sides and back of the garment and to the front thereof for interengagement of its free end with the free end of the companion band.
